UNITED STATES PATENT OFFICE.

LEO WEINER, OF PROVIDENCE, RHODE ISLAND.

DESIGN FOR A CHARM.

60,504.

Specification for Design.

Patented Feb. 28, 1922.

Application filed October 15, 1921. Serial No. 508,024. Term of patent 14 years.

To all whom it may concern:

Be it known that I, LEO WEINER, a citizen of the United States, residing at Providence, in the county of Providence and State of Rhode Island, have invented a certain new, original, and ornamental Design for a Charm, of which the following is a specification.

In the accompanying drawings which form a part of this specification,

I claim:

The ornamental design for a charm, as shown.

LEO WEINER.
